(57) **CLAIM**

The ornamental design for binoculars, as shown and described.

DESCRIPTION

FIG. 1 is a top, front and right side perspective view of binoculars showing my new design.

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled “9” framed in FIG. 1; and,

FIG. 10 is an enlarged view of the portion labeled “10” framed in FIG. 1.

The evenly dashed broken lines show portions of the article and form no part of the claimed design. The unevenly dashed broken lines demarcate the boundaries of the enlarged views and form no part of the claimed design. The dash-dot-dash lines in the drawings represent boundaries of the claimed design and form no part thereof.
